UNITED STATES PATENT OFFICE.

BRONSON C. SKINNER, OF DUNEDIN, FLORIDA, ASSIGNOR TO SKINNER MACHINERY COMPANY, OF DUNEDIN, FLORIDA, A CORPORATION OF FLORIDA.

ORCHARD HEATER.

Application filed July 13, 1923. Serial No. 651,232.

To all whom it may concern:

Be it known that I, BRONSON C. SKINNER, a citizen of the United States, residing at Dunedin, in the county of Pinellas and State of Florida, have invented certain new and useful Improvements in Orchard Heaters, of which the following is a specification.

The present invention comprises an orchard heater of such construction that the parts thereof may be quickly assembled without the use of bolts or securing means ordinarily employed for uniting or holding together the associated structural members of a heater, the structure of the present heater being such as to permit of its members to be quickly taken apart or dismounted to enable the same, if so desired, to be shipped from place of manufacture to distant points in a knocked down condition and quickly assembled when desired for use in connection with the heating of orchards; the object of the invention being the production of an orchard heater economical in its construction, cheap as to manufacture and yet efficient for the work required.

To comprehend the invention reference should be had to the accompanying sheet of drawings, wherein—

Fig. 1 is a view of the heater in assembled condition.

Fig. 2 is a cross sectional plan view taken on the line 2—2, Fig. 1 of the drawings.

Fig. 3 is a broken detailed view of the grate bar of the heater with one of the supporting legs assembled therewith.

Fig. 4 is a sectional side view in elevation of the parts disclosed by Fig. 3 of the drawings.

Fig. 5 is a broken detail perspective view of the grate bar.

Fig. 6 is a broken perspective view disclosing the upper portion of one of the supporting legs of the orchard heater.

Fig. 7 is a broken detailed plan view disclosing the manner of securing the body in closed or cylindrical form.

In the drawings, the numeral 1 is used to designate the body of the orchard heater, 2 the grate thereof arranged within the lower portion of the body structure when the body is placed in cylindrical form or closed. The side or free edges of the body are flanged over to provide interlocking

hooks 5—5', the interlocking of said hooked edges holding the body member in cylindrical position.

The grate 2 is provided with a plurality of open lateral dove-tailed seats 6 which are adapted to receive the dove-tailed head extension 7 of the supporting legs 8, which said legs are formed with supporting shoulders 9 onto which the grate bar rests and is supported when the parts are in assembled relation; the dove-tailed head 7 of the leg sliding within the dove-tailed seat 6 of the grate, so that when the leg is fitted to the grate bars the same are held so to speak interlocked one with the other. The dove-tailed head 7 of the supporting legs 8 are each formed with an outwardly projected stud 10, preferably circular in cross section and these studs fit through the perforations or openings 11 formed in the bottom portion of the body 1.

When it is desired to assemble the orchard heater for the holding of coke or other fuel medium, the leg members 8 are assembled relative to the grate 2 by the dove-tailed head extensions 7 of the legs being slidably fitted within the dove-tailed seat 6 of the grate, so that at such time the grate bar is held in position by the wedging effect of the leg members 8 applied thereto and prevented from disengaging with the leg members due to the fact that at such time the under surface of the grate rests upon the shoulders 9 of the legs. The body 1 which is then in flattened condition is bent or curved around the assembled grate and legs, the projections or studs 10 of the supporting legs 8 fitting through the openings 11 formed in the lower portion of the body member and the body is united and held in cylindrical form so as to embrace the grate by the hooked edges 5 and 5' thereof being placed in locked engagement.

As thus assembled the supporting legs and the grate 2 are embraced by the body member 1 and securely held thereto on the hooked edges of the body 1 being placed in locked engagement. It will thus be noted that the various members of the orchard heater are assembled and held in locked engagement one with the other without the employment of bolts, screws or other non-associated mechanical attaching members.

To disengage or place the orchard heater in knocked down formation, it is only necessary to compress the body member 1 until the hooked edges 5—5' thereof are disengaged, when the spring of the metal will separate or flatten out the body and disengage the same from the lugs of the supporting legs 8 so as to release the grate and the supporting legs from the body member, 10 after which the legs are slipped from engagement with the grate and the heater thus placed in a knocked down or disassembled condition.

It is obvious from the foregoing that the 15 parts of the orchard heater may be constructed or manufactured at one point and shipped in a knocked down condition to consumers or users of orchard heaters situated at distant points and at such points be 20 placed in assembled condition for use in the orchards. By this construction a larger number of orchard heaters may be shipped than when in assembled or made up condition; thereby materially reducing the cost 25 of transportation or shipment of orchard heaters and inasmuch as the orchard heater is capable of being quickly dismantled or placed in disassembled condition, less storage room is required to take care of the 30 heaters after a season's use than where it is required to store the same in assembled condition and furthermore, the interior structural parts of the heater are accessible 35 at all times for the cleaning thereof and for repair purposes.

When the orchard heater is in assembled condition and ready for use, air for supporting combustion therein is admitted to the interior thereof through the draft inlet 40 openings 12 formed circumferentially thereof and adjacent to its bottom end, and the said heater is provided with the usual swinging handle or bail 13 to enable the same to be conveniently moved from place to place.

45 Due to the arrangement of the associated members of the heater and the ease and facility with which said members may be assembled and dismantled, the said constructed orchard heater may be considered and 50 treated as one composed of self-interlocking members, in contra-distinction to the present mechanical unitized secured members. In other words, the present orchard heater is a collapsible one in its entirety and made 55 so for simplicity of construction and ease as to transportation of its parts.

Any form of supporting legs which when 60 assembled relative to their cooperating members will support and uphold the same against displacement, may be employed in the carrying out of my invention, just so long as the same co-operate with the body member for inter-locking with the same when placed in cylindrical or closed formation 65 and by so doing serving to maintain the

grate of the heater in proper relation with the body member.

While the head portion of the supporting legs is disclosed as dove-tailed for inter-locking with suitably shaped seats formed in the 70 grate member of the heater and provided with shouldered extensions for supporting the grate when the said parts stand in assembled relation, and further provided with laterally projecting lug extensions for engagement with openings formed in the body of the heater for receiving the same as placed in cylindrical or closed formation, it is obvious that the supporting legs may be constructed in various forms or shapes for 80 securing interlockability with their cooperating members of the orchard heater. Further, while the body member of the heater is preferably provided with flanged interlocking edges for the holding of the same 85 in proper shape when the parts of the heater are placed in assembled position, it is apparent that any suitable form of locking means may be resorted to for maintaining the said body in closed position relative to 90 its associated structural members.

While the invention has been illustrated and described in its preferred embodiment, I do not wish to be understood as limiting or confining the invention to such detailed 95 construction of its structural parts, but, on the contrary, wish to be understood as claiming the invention as broadly as the state of the art will warrant.

What I claim and desire to secure by Letters Patent, is:

1. A knock down orchard heater, the same comprising a grate member provided with seats for the reception of supporting leg members, supporting legs carrying a head extension adapted to interlock with and support the grate member and provided with means for interlocking with the body member of the heater, and a foldable body adapted to embrace the legs and grate members of the heater when placed in closed condition and provided with means for holding the edges thereof in locked engagement.

2. In combination with a foldable body member of an orchard heater, of a grate member adapted to be supported therein, and supporting leg members adapted to interlock with the grate members for the support thereof and provided with means for interlocking with the body member when held in closed formation.

3. In combination with the grate member of an orchard heater, a grate member provided with seats for the reception of supporting legs, of supporting legs carrying a head extension adapted to interlock with the seats of the grate for supporting the same, and provided with means for interlocking with the body member.

4. An orchard heater comprising a fold-

able body member, a grate therefor, and supporting legs adapted to inter-lock with the grate member and with the body member when placed in closed position.

5 5. In a foldable orchard heater and in combination with the grate thereof, of a plurality of supporting legs each carrying a head extension for inter-locking with and supporting the grate member and provided

10 with means for interlocking with the body member when placed in closed position.

6. An orchard heater comprising a foldable body member provided with means for holding the same in closed position, a grate

15 provided with a plurality of dove-tailed seats, a plurality of supporting legs each provided with a dove-tailed head extension for interlocking with the seats of the grate and shouldered extensions for supporting

20 the grate when the members are interlocked, said supporting legs being provided with stud extensions for engaging with the body member of the heater as placed in closed condition to embrace the legs and grate.

25 7. A disengageable orchard heater, the same comprising a foldable body member, a grate member and supporting leg member, said respective members provided with means whereby the same are adapted for

30 interlocking one with the other on the body member being placed in closed position, and said body member carrying means for hold-

ing the side edges thereof in locked engagement.

8. An orchard heater comprising a foldable body member, a grate member for mounting relative to the body member, and supporting leg members provided with means adapted to inter-lock with the grate member and the body member on the latter

35 member being placed in closed condition.

9. An orchard heater comprising a foldable body member provided with means for holding the side edges thereof in locked position, a grate member adapted for mounting within the body member when same is in closed position, supporting leg member carrying means for inter-locking with and supporting the grate member, and means carried by said leg members for interlocking

40 with the body member when in closed condition to embrace the legs and grate.

10. The combination in an orchard heater, of a dismountable grate member provided with a plurality of seats for the reception

45 of leg members, of supporting leg members provided with a head extension adapted to inter-lock with the grate member for the support thereof and carrying a lug extension for interlocking with the body member

50 of the heater.

In testimony whereof I have signed my name to this specification.

BRONSON C. SKINNER.
